FOLDING BRACE

Filed Sept. 20, 1928

INVENTOR
Henry J. Gilbert
BY George P. Willcox
ATTORNEY

UNITED STATES PATENT OFFICE

HENRY J. GILBERT, OF SAGINAW, MICHIGAN, ASSIGNOR TO SAGINAW MANUFACTURING CO., OF SAGINAW, MICHIGAN, A CORPORATION OF MICHIGAN

FOLDING BRACE

Application filed September 20, 1928. Serial No. 307,211.

This invention is a folding brace for collapsible tables and for similar uses where the brace when extended is subjected to considerable endwise thrust and consequently must be capable of withstanding considerable strain in operation without buckling or springing flatwise.

An object of the invention is, therefore, to so arrange the overlapping pivotally joined ends of the bars, and to so offset them in relation to each other at the joint, that the two bars when extended to form the brace will lie as nearly as possible in the same plane, in order that the extended brace, when put into compression by loads applied at its ends, will have a minimum of tendency to buckle in the vicinity of the joint.

A further object of the invention is to so locate and arrange the above-mentioned offset on one of the bars as to enable it to also serve as a lateral stop for the projecting end of the other bar when the bars are extended, for the purpose of holding the joint members in alignment.

The inventive novelty as claimed herein is found in the combination of the two pivotally joined bars with an offset part in one bar that serves the double purpose of aligning both bars as nearly as possible in the same plane, viz, the plane in which they move when folding, and of supplying a stop member which restrains the bars against lateral movement, thereby holding the joint in locked position.

With the foregoing and certain other objects in view, which will appear later in the specification, my invention comprises the devices described and claimed and the equivalents thereof.

In the drawings Fig. 1 is a perspective view of the joint in extended position, the slidable catch retracted.

Fig. 2 is a similar view showing the joint open.

Fig. 3 is an edge view, partly sectional, of the brace extended.

Figs. 4 and 5 are respectively top and bottom views of the joint shown in Fig. 3.

Fig. 6 is a perspective detail of the slidable catch.

As is clearly shown in the drawings, the

brace proper consists in the usual bars 1, 2 pivotally joined at 3, a projecting portion 1a of bar 1 being in overlapping relation to bar 2 when the brace is extended. The overlapping part 1a is formed at its end with a notch so as to present a tongue 4 that overlies the pivoted end of bar 2.

Close to the extremity of tongue 4 there is formed in bar 2 an upward offset at 5 so as to bring the bar 2 and the overlapping part 1a of bar 1 into the same plane, as shown by the center line in Fig. 3.

The offset 5 in bar 2 is formed with a struck-up abutment 5a whose side wall 5b engages the corresponding side wall 4c of the tongue when the bars 1, 2 are extended.

A catch 6, slidable on bar 2 and formed with a side wall 6a serves as a releasable keeper for tongue 4.

By shaping the bar 2 with the offset 5 located close to the end of tongue 4, and by forming the offset to provide the abutment-member 5a I attain the two desired results above referred to, namely, the bars 1 and 2 are kept more nearly in the same longitudinal plane and, therefore, more nearly like a single straight bar when they are extended, the amount of relative lateral offset being small, as shown at A in Fig. 3, that is, merely enough to give folding clearance for bar 1 over the catch 6. Consequently there is very little tendency to buckle under end thrust and a bar of thin material will resist a relatively heavier end thrust than is possible when the joint is constructed so that the offset distance A is greater than in the present device.

The second advantage attained by this construction is that the offset 5 being located close to the end of keeper 4 is easily formed with the abutment 5b, against which the side wall 4c of tongue 4 engages.

The catch 6 is preferably of the gravitational type and can be slid into place after the brace 1 is extended, either by hand or if the brace is at a suitable angle it will engage automatically by gravity.

Having thus described my invention, what I claim and desire to secure by Letters Patent is:

In combination, a pair of pivotally joined

bars one of which has an extended portion in overlapping relation with the other bar, the end of said overlapping part notched to form a tongue, the other bar provided, near 5 said tongue, with an offset flatwise to bring the two bars approximately into the same plane, said offset portion formed with a longitudinal slit, the metal at one side of said slit formed to present a struck-up abutment 10 member whose side edge engages the corresponding side edge of the tongue on the first-mentioned bar when the bars are extended, and a slidable catch on said second bar arranged to overlap both said offset portion 15 and said overlapping portion when the bars are extended, for the purposes set forth.

In testimony whereof, I affix my signature.
HENRY J. GILBERT.
